STEVEDORE JACK

Benjamin N. Williams, Beacon, and Thomas D. Sanford, New York, N. Y.

Application May 11, 1944, Serial No. 535,058

7 Claims. (Cl. 254—130)

This invention relates to new and useful improvements in a stevedore jack.

More specifically, the invention proposes the construction of a stevedore jack arranged in a manner to provide a base having an upwardly extending super-structure upon which a crowbar is adapted to be pivotally mounted to be fulcrumed about the superstructure to facilitate the speedy loading and unloading of ships and lifting heavy objects around docks, warehouses, and other similar places.

A further object of the invention proposes providing the superstructure with several pairs of fulcrum sockets at different elevations which are adapted to be selectively engaged by trunnions formed on the crowbar for permitting the angular and elevated position of the crowbar relative to the superstructure to be adjusted to meet the lifting requirements of each individual job.

A further object of the invention proposes providing the stevedore jack with a box-like base encasing a pressure plate provided with spurs adapted to be projected from the base in a manner to grip the floor or other surface upon which the jack is rested to prevent it from slipping during the lifting operation.

Still another object of the invention proposes providing the base with a cam shaft and cam provided for lifting and lowering the pressure plate relative to the base in a manner to engage these spurs with the floor surface.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a side elevational view of a stevedore jack constructed in accordance with this invention.

Fig. 2 is a plan view of Fig. 1 with the crowbar removed therefrom.

Fig. 3 is an enlarged vertical sectional view taken on the line 3—3 of Fig. 1.

Fig. 4 is a partial vertical sectional view taken on the line 4—4 of Fig. 3.

Fig. 5 is a partial vertical sectional view taken on the line 5—5 of Fig. 2.

Fig. 6 is a perspective view of the bottom portion of the crowbar, per se.

The stevedore jack, according to this invention, comprises a box-like base 10 having a superstructure 11 mounted upon the top thereof.

The box-like base 10 has an open top closed by means of a plate 12 forming a portion of the superstructure 11 and which is securely held in position by screws 13 which pass threadedly through the plate 12 and engage complementary lugs 14. The lugs 14 are formed on the inside faces of the walls of the box-like base 10. The superstructure 11 further includes a pair of laterally spaced vertical walls 15 which extend upwards from the plate 12. The vertical walls 15 are reinforced by buttresses 16 which are integrally formed between the outer faces of the walls 15 and the top face of the plate 12. The top portions of the vertical walls 15 are provided with several pairs of fulcrum sockets 17 arranged at different elevations. The buttresses 16 have short lengths of metal 18 extended therethrough to provide handles by which the base portion of the stevedore jack may be lifted.

A crowbar 19 is provided for use in connection with the fulcrum sockets 17 of the superstructure 11. This crowbar 19 comprises a bar portion having a flattened nose 21 which is adapted to be engaged beneath the article to be lifted by the stevedore jack and also as a pry between two objects. The back end of the bar portion 20 has a threaded shank 21 upon which a lever bar 22 is adapted to be threadedly engaged. The top of the bar portion 20 is formed with a projected threaded stud 23 upon which a foot pressure bar 24 is threadedly engaged. On the side of the bar portion 20, opposed to the portion provided with the threaded stud 23, a depending lug 25 is formed from which trunnions 26 extend in opposite directions. In engaging the crowbar 19 upon the superstructure 11 the bottom portion of the lug 25 is projected into the space between the adjacent faces of the vertical walls 15 of the superstructure 11 permitting the trunnion elements 26 to be engaged with the fulcrum cutouts 17.

The elevated portion of the crowbar 19 may be adjusted by engaging the trunnion elements 26 with a desired pair of the fulcrum sockets 17. It will be found that by adjusting the position of the trunnion elements 26 relative to the superstructure 11 that a position may be determined giving the best mechanical advantage for lifting a given article from the surface upon which the stevedore jack is rested.

A pressure plate 27 is vertically slidably mounted within the base 10. This pressure plate is provided with a plurality of downwardly projecting spurs 28 which are adapted to be projected through complementary openings 29

formed in the base wall of the box-like base 10 to engage a surface upon which the stevedore jack is resting to prevent the jack from slipping. The top ends of the spurs 28 are threadedly engaged with the pressure plate 27 and the bottom ends thereof are pointed and directed in a manner to rigidly engage the surface upon which the jack is resting.

Means is provided for lifting and lowering the pressure plate 27 relative to the base wall of the box-like base 10 to extend and retract the spurs 28 relative to the openings 29. This means comprises a cam shaft 30 which is rotatively extended laterally through the box-like base 10 and which is provided at its center with a cam 31. This cam 31 is extended through complementary cam shaped openings 32 formed in vertical walls 33 which extend from the top face or the pressure plate 27. Rotations of the cam shaft 30 will be transmitted to the cam 31 and due to its extension through the cam shaped openings 32 it will cause the pressure plate 27 to be lifted and lowered.

One end of the cam shaft 30 is extended from the box-like base 10 and has a pivoting lever 34 fixedly attached thereto. This pivoting lever 34 is provided at its free end with a foot pedal 35 which is adapted to be stepped upon for applying pressure thereto to cause the cam shaft 30 to return and extend the spurs 28 from the openings 29 and dig them into toe surface upon which the stevedore jack is rested. The box-like base 10 is provided with outwardly extended lugs 36 upon which the pivoting lever 34 is adapted to rest. With the lever 34 in the position shown in Fig. 2 the pressure plate 27 will be in the inoperative position shown in Figs. 3 and 4. However, if the lever 34 is pivoted through substantially, 180° to rest upon the lug 36 on the other side of the box-like base 10 the pressure plate 27 will be moved to its operative position and the spurs will be projected from the base thereof.

The manner of using the stevedore jack, according to this invention, is as follows:

The box-like base 10 together with its superstructure 11 is rested upon the surface of a floor adjacent an object to be lifted and the lever 34 is pivoted to move the pressure plate 27 downwards within the box-like base 10. This will extend the spurs 28 from the bottom of the box-like base 10 and dig them into the surface to retain the base against moving relative to the floor surface. The crowbar 19 then has its trunnion elements 26 engaged with a given pair of fulcrum sockets 17 at the desired elevation and the flattened nose 21 thereof is engaged beneath the article to be lifted. The crowbar 19 is then pivoted about the trunnion elements 26 through the medium of the bars 22 and 24 to cause the article to be lifted to the desired elevation to permit a dolly or other similar caster element to be engaged beneath the object so that it may be moved about.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:

1. A stevedore jack, comprising a box-like

base, a superstructure mounted on said base and having a pair of laterally spaced vertical walls with several pairs of fulcrum sockets at different elevations, a crowbar provided with a trunnion for engaging a pair of said fulcrum sockets, a pressure plate within said base and provided with spurs for projecting from apertures in the bottom wall of said base, and a cam shaft with a cam for raising and lowering said pressure plate.

2. A stevedore jack, comprising a box-like base, a superstructure mounted on said base and having a pair of laterally spaced vertical walls with several pairs of fulcrum sockets at different elevations, a crowbar provided with a trunnion for engaging a pair of said fulcrum sockets, a pressure plate within said base and provided with spurs for projecting from apertures in the bottom wall of said base, and a cam shaft with a cam for raising and lowering said pressure plate, said superstructure being characterized by a bottom plate closing the top of the box-like base and said vertical walls being extended from said plate.

3. A stevedore jack, comprising a box-like base, a superstructure mounted on said base and having a pair of laterally spaced vertical walls with several pairs of fulcrum sockets at different elevations, a crowbar provided with a trunnion for engaging a pair of said fulcrum sockets, a pressure plate within said base and provided with spurs for projecting from apertures in the bottom wall of said base, and a cam shaft with a cam for raising and lowering said pressure plate, said superstructure being characterized by a bottom plate closing the top of the box-like base and said vertical walls being extended from said plate, and buttresses provided between the outer faces of said walls and the top face of said plate.

4. A stevedore jack, comprising a box-like base, a superstructure mounted on said base and having a pair of laterally spaced vertical walls with several pairs of fulcrum sockets at different elevations, a crowbar provided with a trunnion for engaging a pair of said fulcrum sockets, a pressure plate within said base and provided with spurs for projecting from apertures in the bottom wall of said base, and a cam shaft with a cam for raising and lowering said pressure plate, said superstructure being characterized by a bottom plate closing the top of the box-like base and said vertical walls being extended from said plate, and buttresses provided between the outer faces of said walls and the top face of said plate, and handles mounted on said buttresses.

5. A stevedore jack, comprising a box-like base, a superstructure mounted on said base and having a pair of laterally spaced vertical walls with several pairs of fulcrum sockets at different elevations, a crowbar provided with a trunnion for engaging a pair of said fulcrum sockets, a pressure plate within said base and provided with spurs for projecting from apertures in the bottom wall of said base, and a cam shaft with a cam for raising and lowering said pressure plate, said crowbar being characterized by a bar portion having a flattened nose, a lever bar mounted on the back end of said bar portion, a foot pressure bar mounted on the front of said bar portion, a depending lug formed on the back of said bar portion, and said trunnion element being formed on said depending lug.

6. A stevedore jack, comprising a box-like

base, a superstructure mounted on said base and having a pair of laterally spaced vertical walls with several pairs of fulcrum sockets at different elevations, a crowbar provided with a trunnion for engaging a pair of said fulcrum sockets, a pressure plate within said base and provided with spurs for projecting from apertures in the bottom wall of said base, and a cam shaft with a cam for raising and lowering said pressure plate, said spurs having their bottom ends pointed to dig into a surface when projected from said box-like base. 10

7. A stevedore jack, comprising a box-like base, a superstructure mounted on said base and having a pair of laterally spaced vertical walls with several pairs of fulcrum sockets at 15

different elevations, a crowbar provided with a trunnion for engaging a pair of said fulcrum sockets, a pressure plate within said base and provided with spurs for projecting from apertures in the bottom wall of said base, and a cam shaft with a cam for raising and lowering said pressure plate, and said cam shaft being extended laterally through said box-like base, a cam formed on said cam shaft within said box-like base and engaging cam openings formed in walls extending from said pressure plate, and means mounted on said cam shaft externally of said box-like base for turning the shaft to lift and lower the pressure plate. 5
